UNITED STATES PATENT OFFICE

EDWARD W. ISOM, OF SCARSDALE, NEW YORK, AND EUGENE C. HERTHEL, OF CHICAGO, ILLINOIS, ASSIGNORS TO SINCLAIR REFINING COMPANY, OF NEW YORK, N. Y., A CORPORATION OF MAINE

ART OF CRACKING HYDROCARBONS

Application filed June 11, 1929. Serial No. 370,097.

This invention relates to improvements in the manufacture of lower boiling hydrocarbon oils, such as gasoline, from higher boiling hydrocarbon oils, such as gas oil, by pressure cracking operations.

The present invention provides a combined operation including a novel heating operation of special value and application in conjunction with operations in which high boiling oil 10 is heated to a cracking temperature under high pressure and in which the hot oil products of this heating operation are separated into a vaporized fraction and an unvaporized fraction under lower pressure, or so-called 15 "pressure coil" cracking operations.

The invention will be described in connection with the accompanying drawings which illustrate, diagrammatically and conventionally, apparatus embodying and for carrying 20 out the invention. In the accompanying drawings, Fig. 1 represents, in elevation and partly in section and with parts broken away, apparatus embodying and adapted for carrying out the invention, Fig. 2 is a fragmentary section through and just above the lower ends of the heating tubes illustrated in Fig. 1, and Fig. 3 is a fragmentary section similar to Fig. 2 illustrating a modified arrangement of the heating tubes.

30 Referring to the drawings, a stream of high boiling oil is forced, by means of pump 2, successively through two batteries of series connected vertical heating tubes arranged in a vertical heating flue in heating furnace 1, then through a pressure reducing valve 3, and into a vapor separating receptacle 4 from which vapors are taken off under reduced pressure, the oil being heated to a cracking temperature during passage through the heating tubes. The two batteries of heating tubes, 5 and 6, each consists of a plurality of series connected banks of heating tubes each of which banks consists of a plurality of series connected heating tubes. These several 45 banks of heating tubes are arranged transversely to the general direction of travel of the heating gases entering the upper end of the vertical heating flue in which these banks of heating tubes are arranged so that the heating gases entering the upper end of the heat-

ing flue flow across the several banks of heating tubes in succession, first across the banks of heating tubes comprising the battery 5 and then across the banks of heating tubes comprising the battery 6. The heating gases entering the upper end of the vertical heating flue 7 through passage 8 from the firebox 9, in which fuel is burned for supplying heat to the operation, and after passing across and back and across the heating tubes while flowing generally downwardly through the heating flue 7 escape through stack flue 10. The oil flowing through each bank of heating tubes flows successively upwardly and downwardly through the series connected heating tubes forming the bank. The oil supplied to the two batteries of heating tubes, through connection 11, flows first through battery 5 and then through battery 6, being discharged through connection 12. Thus, the heating 55 gases from the firebox 9 pass across the upper end of the heating flue 7, as they enter it through passage 8, passing first over the heating tubes comprising the battery 5 through which the oil supplied to the two batteries of 60 heating tubes first passes and then over the heating tubes comprising the battery 6 through which the oil supplied to the two batteries of heating tubes last passes, and these heating gases then pass generally downwardly through the heating flue 7 over the heating tubes comprising the two batteries 5 and 6 to the stack flue 10.

In the modified arrangement of heating tubes illustrated in Fig. 3, the heating gases 65 similarly pass first over the heating tubes comprising the battery through which the oil supplied to the two batteries of heating tubes first passes and then over the heating tubes comprising the battery through which the oil supplied to the two batteries of heating tubes last passes. The order of oil flow through the several banks of heating tubes comprising the battery of heating tubes 70 through which the oil first passes, battery 5, is reversed as compared to the order of oil flow through the banks of heating tubes comprising the battery 5 in Fig. 2. Corresponding parts are designated by the same reference characters in Figs. 2 and 3. 75

As the hot oil products discharged through connection 12 pass the pressure reducing valve 3, the pressure thereon is reduced, from a pressure of several hundred pounds per square inch to a pressure approximating atmospheric pressure for example. In the vapor separating receptacle 4, a vaporized fraction is separated from an unvaporized fraction. The vapors comprising the vaporized fraction are taken off through connection 13 and are subjected to a refluxing operation in reflux tower 14 from which the vapors remaining uncondensed escape through connection 15 to a condenser 16 arranged to discharge into a receiver 17 from which a condensed distillate product is discharged through connection 18 and uncondensed vapors and gases through connection 19. A superatmospheric pressure, lower however than the pressure under which the hot oil products are discharged from the second battery of heating tubes, may be maintained in the vapor separating receptacle 4 and the reflux tower 14 and regulated by means of valve 20, or by means of suitable valves arranged beyond the condenser or receiver. Raw oil or some other refluxing medium is supplied to the refluxing operation through connection 21 by means of pump 22, and utilized therein as a direct refluxing medium for effecting and controlling the operation. Reflux condensate, or admixed reflux condensate and raw oil, is supplied to the batteries of heating tubes arranged in the heating furnace 1 from the refluxing operation through connections 23 and 11 by means of pump 2. Raw oil, or additional raw oil, may also be supplied to the vapor separating receptacle through connection 24. Residual oil, the unvaporized fraction separated in the vapor separating receptacle, is discharged from the vapor separating receptacle 4 through connection 25.

In initiating operation, oil, supplied through connection 24, is circulated from the vapor separating receptacle 4, by means of valved connection 26, through the batteries of heating tubes and back to the vapor separating receptacle until normal operating conditions of temperature and pressure are reached, the valve in connection 26 being closed during normal operation. The supply of oil through connection 24 may or may not be continued during normal operation. Connection 27, communicating through valved branches with the lower ends of each of the heating tubes, is provided for pumping out the battery of heating tubes at the end of a run. The vapor separating receptacle 4 is pumped out at the end of a run through connection 28.

In carrying out the invention in the apparatus illustrated, vapors may be taken off from the vapor separating receptacle 4 under a pressure in the general range of 1-10

pounds per square inch or under a somewhat higher pressure, for example, and the oil forced through the batteries of heating tubes may be heated therein to a temperature approximating 900-950° F., as discharged therefrom, under a pressure in the general range of 300-600 pounds per square inch, as discharged therefrom, for example. The rate at which raw oil, or other refluxing medium, is supplied through connection 21 may be regulated to condense in the refluxing operation all constituents higher boiling than suitable as components of the desired distillate product, and residual oil may be discharged through connection 25 at a rate regulated to maintain a uniform liquid level in the vapor separating receptacle 4. Cool raw oil may be supplied through connection 24, during normal operation, to arrest the cracking reaction initiated in the batteries of heating tubes.

In the apparatus illustrated, the vapor separating receptacle 4, the reflux tower 14 and connections 12, 13, 23 and 11 are with advantage thoroughly lagged or thermally insulated.

The heating furnace 1 may, with advantage, be arranged and operated as described in Letters Patent Nos. 1,574,546 and 1,574,547 issued to Sinclair Refining Company, February 23, 1926, on application of the late John E. Bell or as described in Letters Patent No. 1,623,773 issued to Sinclair Refining Company, April 5, 1927, on application of the late John E. Bell.

The present invention has a number of advantages. The combination of vertical oil flow and high velocity oil flow in the heating operation minimizes any tendency toward deposition of pitch or carbon in the heating tubes. The arrangement of the heating tubes is peculiarly compact and permits the use of a gang cleaner with maximum advantage. The heat exchange relations between the heating gases and the oil being heated to a cracking temperature, provided by this invention, are peculiarly effective in so-called "pressure coil" cracking operations.

We claim:

In the manufacture of lower boiling hydrocarbon oils from higher boiling hydrocarbon oils, the improvement which comprises forcing a stream of high boiling oil successively through two batteries of series connected vertical heating tubes arranged in a vertical heating flue through a pressure reducing valve into a vapor separating receptacle, passing heating gases from a firebox in which fuel is burned for supplying heat to the operation across the upper end of said heating flue first in heat exchanging relation with the oil in the battery of heating tubes through which the oil first passes and then in heat exchanging relation with the oil in the battery of heating tubes through which the oil

oil last passes and then passing the heating gases generally downwardly through said heating flue in heat exchanging relation with the oil in said batteries of heating tubes, and thereby heating the oil to a cracking temperature, maintaining a superatmospheric pressure on the oil in said batteries of heating tubes and taking off vapors including vapors of the desired low boiling oil from said vapor separating receptacle under reduced pressure.

In testimony whereof we affix our signatures.

EDWARD W. ISOM.
